METHOD OF DETERMINING LOCATION OF LIQUID LEVEL IN WELLS

Cranford P. Walker, San Marino, Calif.

Original application October 26, 1937, Serial No. 171,170. Divided and this application April 19, 1939, Serial No. 268,806

6 Claims. (Cl. 181—0.5)

My invention relates to methods and apparatus for determining the location of the liquid level in deep wells such as oil wells and the like, and has particular reference to methods and apparatus which may be readily and economically employed upon wells having a mechanical pump therein to determine when the liquid level is at or immediately adjacent to the inlet of such pump.

This application is a division of my copending application Serial No. 171,170, filed October 26, 1937, wherein is described and claimed methods of determining the density of the liquid in the standing column about the pump and pump tubing for determining the pressure existing in the standing column at any point below the normal liquid level and for determining the maximum production capacity of a well all of which methods utilize the measurement of the location of the liquid level in the well.

It is the common practice in oil well production activity to permit an oil well to produce as a flowing well, that is, to permit the oil to flow out at the ground surface due to the pressure in the oil formations, until the production rate reaches a considerably low value or ceases, after which gas lifting is usually attempted and continued until the production rate with gas lifting reaches a relatively low value or the production entirely ceases. At this time, and in some instances prior to any attempt to gas lift the oil, mechanical pumping devices are usually installed to lift the oil by mechanical means to the surface, these pumps usually comprising a pump barrel located at a considerable depth in the well, usually 50 to 150 feet below the surface of the liquid in the well while it is producing, plungers or other reciprocating devices being employed in the barrel and operated from the ground surface by means of sucker rods.

Usually the selection of the size and character of the pumping equipment is determined by the production of the well during its flowing or gas lifting life by estimating from this production the type or character of pump which appears to be most suitable. In many fields, however, the type, size and character of the pump installed is usually one determined as "standard" for that particular type of well in the particular field. In other words, it is one having the same dimensions as pumps in other wells producing from the same horizon. Frequently, such well receives no further attention until the field as a whole has declined to a point where it becomes necessary to increase the production from the wells, as for

example, by the encroachment of water, necessitating the lifting of greater quantities of fluid in order to obtain the desired amount of oil. When this condition occurs, it is customary to increase the capacity of the pumping equipment.

For example, if the pumps in the particular field are operating at good volumetric efficiency, much can be determined from the quantity of oil produced and the volumetric displacement per stroke of the pump, and if the pumps are operating at their maximum capacity, the fact that the fluid level is at a considerable distance above the pump inlet may indicate that the operator is justified in making a change in the size or character of the pumping equipment. Again, if the volumetric efficiency of the pump is found to be low, as for example, when the pump appears to be taking in a comparatively large quantity of gas upon each stroke of the pump, the operator should know whether or not the inlet of the pump is located at a point too near the liquid surface so that he may determine how far below the liquid surface he should lower the pump in order to allow it to receive liquid for the full stroke.

To determine the correct location of the pump, it is desirable to know the normal pressure at the pump inlet when the pump is producing oil from the well and this determination may be made in many wells by moving the liquid surface to a position so close to the pump inlet that the pump will take in free gas upon each cycle of its operation.

The entry of free gas into the pump will produce pressure waves within the gas column or annular space between the pump tubing and the casing of the well, which pressure waves will travel to the ground surface and there may be detected by suitable pressure responsive mechanism such as is illustrated and described in my copending application Serial No. 164,534, filed September 18, 1937, and in United States Letters Patent No. 2,156,519, issued to me on May 2, 1939.

By properly observing or recording these pressure waves at the ground surface, they may be readily distinguished from other pressure waves or disturbances in the gas column resulting from other causes. Hence by observing the sound waves or pressure waves produced at the pump, the fact that the fluid level is at or immediately adjacent to the pump inlet may be determined. The information so obtained may be utilized in accordance with the methods for determining pressure and production capacity described and claimed in my copending application Serial No. 171,170 hereinbefore referred to.

It is therefore an object of my invention to

provide a method for determining whether or not the liquid level is at or adjacent to the inlet of the pump by observing the peculiarly distinguishable pressure waves set up as a result of the inflow of gas into the pump, provided there is considerable pressure in the casing of the well.

Another object of my invention is to provide a method and apparatus for so observing the pressure waves or sound waves resulting from inflow of gas into the pump when the level of the liquid is at or adjacent to the pump that this condition may be distinguished from sounds or pressure waves resulting from other causes.

Other objects and advantages of my invention will be apparent from a study of the following specifications, read in connection with the accompanying drawing, wherein

Fig. 1 is a diagrammatic cross sectional view of a typical oil well illustrating the manner in which the location of the liquid surface at the pump inlet may be detected; and

Fig. 2 is a diagrammatic view illustrating the type of record produced by the pressure waves or sound created when the fluid level is at or adjacent to the pump inlet and which may be recorded by the recording apparatus illustrated in Fig. 1.

Referring to the drawing, I have illustrated in Fig. 1 a typical oil well which includes a casing 1 extending down through the well bore from the ground surface 2 into the oil producing sands, the oil flowing from the sands or oil formation into the casing and rising in the casing to some level indicated at 3. Pumping apparatus employed to remove the oil from the well usually includes a suitable pump 4 located upon tubing string 5, constituting the flow tubing through which the oil is raised to the ground surface, the pump 4 including usually some reciprocating mechanism operated by reciprocal movements of a string of sucker rods 6 extending down through the tubing 5 and connected to reciprocating power apparatus at the ground surface, as indicated at 7. The flow tubing 5 is provided with an outlet 8 communicating with a suitable oil line through which the oil pumped from the well is conveyed to any desired location.

The casing 1 is closed at its upper end as indicated at 9, an outlet 10 being provided communicating with the casing 1 to permit gas escaping from the oil to pass into a suitable gas line 11, a control valve 12 being usually provided to control the flow of gas into the gas line.

As will be understood by those skilled in the art, the oil which flows from the formation into the well may be substantially free of gas or may contain relatively large quantities of gas entrained with the liquid so that the pressure of the oil and gas mixture within the well, and particularly in the standing column of liquid in the annular space between the pump tubing and the casing, will vary through relatively wide limits. However, if the pressure existing in the oil and gas mixture can be determined or calculated for any desired point therein below the normal liquid level, this information may be readily used to determine the best location for the pump to insure its maximum volumetric efficiency; that is, since the pump is operating upon a liquid and gas mixture, it is desirable that the pump should be located at the level within the liquid column at which the maximum separation of gas from the mixture occurs else upon each stroke of the pump the pump will take in relatively large quantities of gas which will expand within the

5 pump and seriously reduce its volumetric efficiency. If, however, the pump is properly located in the oil and gas mixture column, at which the gas readily separates from the liquid and bubbles out as free gas to pass up through the casing, the pump will be operating upon relatively dense fluid.

To assist in the determination of the correct 10 location of the pump, the pressure existing at the pump inlet should be known. As is explained in my application Serial No. 171,170, the pressure existing at any point below the normal level of the surface of the standing column of liquid in the well (that is, the dead column of liquid standing in the well as distinguished from the pumped liquid which is being elevated by the pump) may be readily determined by measuring the pressure 15 of gas within the well casing which is required to maintain the liquid level at some known location.

For example, it may be assumed that the height 20 to which the standing column of liquid will rise in the well will be such that the pressure in the formation which causes the oil to flow into the well is just balanced by the height of the liquid column, plus the gas pressure which exists at the casing head of the well, plus the effect in pressure of the column of gas between the liquid surface and the casing head. If the location of the 25 liquid level is known, it follows that by merely measuring the casing head pressure, multiplying the number of feet of gas column existing between the liquid surface and the casing head by the unit weight per foot of the gas, and adding 30 the product so found to the casing head pressure, the pressure at the liquid surface may be accurately calculated. However, unless the location of the liquid surface is known, such pressure determination cannot be made merely from the 35 casing head pressure and the effect in height of the column of gas.

40 In my copending application Serial No. 171,170, I describe a sonic method of determining the location of this liquid level regardless of where the liquid level may be with respect to the location of the pump and thus allow this simple method of determining the pressure to be performed. However, in some instances such pressure determination may be made by introducing 45 gas into the well in sufficient quantities to depress the normal liquid level down to the pump inlet and detecting when the liquid level arrives at the pump inlet. Thus, the location of the pump inlet being known, the calculations of casing head 50 pressure necessary to maintain this liquid level at the pump inlet, plus the effect in height of the gas column between the pump inlet and the casing head, may be readily practiced. If the well is producing reasonable quantities of gas the same effect of depressing the liquid column to the 55 pump inlet may be accomplished by merely closing off the casing head and allowing the escaped gases to build up pressure until the column has 60 been so depressed.

65 As is recited in my copending application Serial No. 171,170, the pressure at the pump inlet may be plotted or calculated against the production rate of the pump for any two rates of production, either the static condition (zero production) and one rate of actual pumping of liquid from the well, or two different rates of actual production (actual pumping of liquid from the well), to provide a productivity index for that well from 70 which the maximum production capacity of that well may be determined.

It follows therefore that by locating the liquid level at or near the pump inlet or depressing the liquid column until the level is at this location and operating the pump under any two rates of production until this liquid level becomes stable for each of those rates of production, this productivity index and production capacity determination may be readily made, particularly in certain wells wherein the mechanical structure of the pumping mechanism and conventional gas anchors permit the successful creation and transmission of the peculiar wave patterns described hereinafter.

I have illustrated and described herein one simple method and apparatus by which the location of the liquid level at or adjacent the pump inlet may be readily determined as comprising a suitable pressure responsive receiving and translating mechanism coupled to the casing of the well in such manner that the pressure waves created at the pump when it takes in free gas may be detected and recorded. This apparatus is illustrated as including a pressure responsive microphone 15 connected directly to the casing head 9 of the well as by means of coupling the same to the gas flow pipe 11 so that variations in pressure existing within the well casing will impinge upon the microphone. This microphone may be of any desired type but I have illustrated herein a microphone and recording apparatus corresponding to that described in detail in my copending application Serial No. 164,534, filed September 18, 1937, the microphone being of the condenser type and being coupled through a suitable amplifier and detector 16 in such manner that the output of the amplifier may be connected to a galvanometer 17 which operates to move a mirror 18 in accordance with the pressure impulses received by or impinging upon the microphone 15. The galvanometer mirror 18 may be used to reflect a light beam 19 from a suitable source of light 20 upon a screen 21 or recording tape or film, the path described by the light beam representing a translation of the pressure waves or sound waves generated at the pump. When the fluid surface is well above the pump, there will be observed a regular wavy pulsation of the light upon the screen or recording film but when the level of the fluid is so depressed that the pump takes in a quantity of free gas upon each stroke, a jerky motion is observed and a pattern will be described which repeats itself for each stroke of the pump. This repetition of similar wave patterns may be readily observed and distinguished from the normal pulsations or wave patterns described as a result of other disturbances; for example, one form of such repeated wave pattern is illustrated in Fig. 2 wherein it will be observed that a series of peaks are produced as indicated at A, B, C and D, these peaks repeated at regular intervals, each representing a stroke of the pump. It will be noted that the peaks A and B represent the pressure changes set up by the surging of the liquid level as the liquid is drawn into the pump while the relatively sharp break X between the peaks B and C represents the beginning of the entry of free gas into the pump, such entry of gas creating a wave of rarefaction which creates the peak C. This same wave pattern is repeated at A', B', X', C' and D' and again at A'', B'', X'', C'' and D''. Thus by observing the wave pattern and noting whether or not there is a distinct break X and the distinct wave of rarefaction C, a skilled operator may determine that

such pattern is caused when the liquid is at or adjacent to the pump inlet. This wave pattern may be observed upon the screen 21 or may be recorded upon a tape recorder such as is commonly known in this art and one form of which is illustrated in my copending application Serial No. 164,534 hereinbefore referred to. It is also possible to employ an audible translating device by which this break in the wave pattern may be detected such as by employing a telephone receiver indicated at 22 coupled to the output circuit shown and described in my copending application Serial No. 164,534.

While in the specific embodiment of the invention illustrated herein, I have shown a condenser type of microphone, it will be understood by those skilled in this art that any other conventional microphone may be employed such as a hot-wire, ribbon or other type of microphone, the characteristics of which will be affected by changes in the pressure existing in pipe 11.

Having this means of knowing when the liquid level is at or near the pump the casing pressure is adjusted to maintain the liquid level a few feet above the pump inlet until the rate of production becomes constant under the increased casing pressure. From the casing pressure required to maintain the liquid level close to the pump the pressure at this level can be determined by adding to the casing head pressure the pressure on the liquid surface caused by the weight of the gas column above it (the liquid surface being at the pump inlet, its density may be disregarded in the calculations for production capacity).

A pressure gauge 13 is usually employed at the casing head for the purpose of measuring the casing head pressure so that by observing this pressure gauge the pressures existing at the casing head when the liquid level is at or adjacent the pump entrance may be readily observed.

It will therefore be observed that I have provided a ready and simple method by which pressure determinations and maximum production capacity determinations may be made upon a well without interrupting the production from the well and without requiring the necessity of removing any of the pump, pump tubing or other apparatus which is employed in the production of the well.

While I have shown and described the preferred embodiment of my invention, I do not wish to be limited to any of the details illustrated or described herein except as defined in the appended claims.

I claim:

1. The method of determining when the surface of the liquid in a well is at the level of a pump inlet, which comprises operating the pump to pump fluid from the well to thus cause surging of the liquid column in the well and pressure variations in the gas column in the well casing, and recording the wave form of the pressure variations in the gas at the casing head of the well to distinguish the smooth wave form produced when the liquid surface level is above the pump from the broken wave form resulting from the intake of free gas into the pump when the liquid surface level is at the pump.

2. The method of determining when the surface of the liquid in a well is at the level of the pump inlet, which comprises operating the pump to pump liquid from the well to thus cause surging of the liquid column in the well and pressure variations in the gas column in the well casing,

changing the casing head pressure to depress the liquid surface toward the level of the pump inlet, recording the wave form of the pressure variations in the gas at the casing head to determine when the smooth wave form produced when the liquid surface level is above the pump changes to a broken wave form resulting from the intake of free gas into the pump when the liquid surface level is at the pump.

3. The method of determining when the surface of the liquid in a well is at the level of the pump inlet, which comprises operating the pump to pump liquid from the well to thus cause surging of the liquid column in the well and pressure variation in the gas column in the well casing, subjecting the gas at the casing head to a pressure responsive device capable of producing movement in response to variations in the gas pressure at the casing head, and observing whether the movements of the pressure responsive device are smooth or abrupt, an abrupt movement denoting entry of free gas into the pump when the liquid surface level is at the pump.

4. The method of determining when the surface of the liquid in a producing well is at the level of the pump inlet, which comprises operating the pump to pump liquid from the well to thus cause surging of the liquid column in the well and pressure variations in the gas column in the well casing, exposing a pressure wave form reproducing device to the gas column in the well casing to reproduce an observable pattern of the form of pressure waves produced in the gas col-

umn, and observing the difference in the form of the pressure waves produced in the gas by the surge of the liquid level caused by removal of liquid by the pump and those waves produced by the entry of free gas in the pump.

5. The method of determining when the surface of the liquid in a producing well is at the level of the pump inlet, which comprises operating the pump to pump liquid from the well to thus cause surging of the liquid column in the well and pressure variations in the gas column in the well casing, exposing a microphone to the gas column in the well casing, and observing the difference in the effect upon the microphone of pressure waves created in the gas by the surge of the liquid level in the well caused by removal of liquid by the pump and those waves produced by the entry of free gas in the pump.

6. The method of determining when the surface of the liquid in a producing well is at the level of the pump inlet, which comprises operating the pump to pump liquid from the well to thus cause surging of the liquid column in the well and pressure variations in the gas column in the well casing, exposing a diaphragm to the gas column in the well casing, and observing the difference in the movement in the diaphragm under pressure waves created in the gas by the surge of the liquid level in the well caused by removal of liquid by the pump and those waves produced by the entry of free gas into the pump.

CRANFORD P. WALKER.
